UNITED STATES PATENT OFFICE.

ALBERT E. BEALL, OF CLINTON, IOWA, ASSIGNOR TO R. N. HOWES AND H. U. CROCKETT.

PAPER-BALER.

1,039,244.

Specification of Letters Patent. Patented Sept. 24, 1912.

Application filed August 11, 1910. Serial No. 576,684.

To all whom it may concern:

Be it known that I, ALBERT E. BEALL, a citizen of the United States, residing at Clinton, county of Clinton, and State of 5 Iowa, have invented a new and useful Improvement in Paper-Balers, of which the following is a specification.

My invention relates to paper balers and has for its object the construction of a baler 10 in which two movable followers are used for compressing the material in the baling chamber. I have also provided simple and efficient means for simultaneously moving the followers toward each other during the 15 baling operation.

The various advantages of my invention will become apparent from the detailed description of the accompanying drawings, in which—

20 Figure 1 is a side view of my invention, showing the interior of the baler; Fig. 2 is an end view of the baler; Fig. 3 is a top view; Fig. 4 is a sectional view taken on line 4—4 of Fig. 2, and Fig. 5 is a fragmental detail view showing how the cable is clamped to the actuating shaft.

The casing or frame-work of the baler, comprises a pair of end pieces 2 and 3, a removable front piece 4 and a back piece 5. 30 The end pieces are provided with foot members 6 for firmly holding the frame-work in an upright position. As shown in Fig. 2, the end pieces consist each of two members separated by the vertical slot 7. A 35 cross-bar 8 serves to hold the members of the end pieces in firm relation to each other. Partitions 9 and 10 form the end walls of the baling chamber 11. In each of the end chambers, formed between the partitions and

40 the end pieces, is located a short shaft 12. This shaft is journaled in bearings 13 and 14 carried by the associated partition and members, as most clearly shown in Fig. 4. As the mechanisms located in the two end 45 chambers are alike, a description of one will be sufficient for both. A cord or cable 15 passes at a point intermediate between its ends through a transverse opening 16 in the shaft 12. At its opposite free ends this 50 cable is adapted to be connected with one end of the upper bar 16 and the lower bar 17. In the particular form shown in the drawings, the opposite ends of the cables are shown in the form of loops which are slipped

over the ends of the bars 16 and 17. It is 55 obvious, however, that any suitable means may be adopted for attaching the cables to the bars. These bars extend longitudinally across the top and bottom of the baling chamber and into the end chambers. Associated with the upper bar 16 is a compression member 18 and associated with the lower bar 17 is a compression member 19. These compression members are loosely associated with their respective actuating bars, 60 and are provided with the grooves 20 on their upper surface to accommodate the actuating bars. The bars 16 and 17, with their associated compression members 18 and 19, constitute the upper and lower followers. 65 If desired, the followers may be made in one piece instead of in two pieces, but I prefer to make them in two pieces because the parts are in that way more readily disassembled. The shafts 12 extend beyond the 70 frame-work at their outer ends where they are each provided with a ratchet wheel 21. The pawl 22 pivoted to the cross-bar 8 at 23, normally engages the teeth of the ratchet wheel 21 and permits the latter to be turned 75 only in the direction in which the shaft 12 will cause the followers to move together. The hook-shaped lever 24 affords ready means for operating the ratchet wheel. As 80 seen from Fig. 2 this lever has at its outer end an inwardly turned hook-portion 25, which is adapted to engage the teeth of the ratchet wheel. The lever is curved at 26 so as to follow the curvature of the ratchet wheel. In this way a fulcrum is provided 85 for the lever, and by simply pressing down on the outer end of the same, the ratchet wheels will be rotated in a counter-clockwise direction, as viewed in Fig. 2. Because of the connection between the actuating bars 16 and 17 and the shaft 12, it is obvious that when the ratchet wheels are operated by the lever, the cables will be simultaneously wound up at both ends and the 90 followers will be moved together. When it is desired to release the followers the pawls 22 are moved out of engagement with the ratchet wheels. To hold the pawls in this 95 their inoperative position, I have provided a latch 27 which engages the free or weight-end of the pawl to hold said weighted end in a raised position.

To prevent slipping of the cable in the

opening in the shaft 12 a wedge 28 is inserted in the opening, as shown in Fig. 5. The back piece 5 and the opposing surface of the followers, are provided with grooves 29 for accommodating the baling wires. As 5 I have stated, the front of the frame-work is removable. For securing this front in place I have provided a number of hinged latch members 30, which hook down over the cross-bars 31 of the front 4, as best 10 shown in Fig. 2. In order to permit ready access to the upper ends of the two cables I provide the top pieces 32 with cutaway portions 33, as best indicated in Fig. 3. The 15 end pieces have cutaway portions 34 which register with the cutaway portions 33 of the top members 32. In this way the hand can be readily inserted into the framework to slip the looped ends of the cables from the 20 upper bar 16—as when it is desired to remove the upper follower.

The operation of my improved baler will now be readily understood from the above description. The material to be compressed 25 is thrust into the baling chamber from the top. After a sufficient quantity has been put in, the upper follower is inserted through the open top and connected with the operating cables. By means of the hooked lever 30 the ratchet wheels are then given each a turn whereby the two followers are brought together sufficiently to compress the material in the baling chamber. Usually, it will not be necessary to give the ratchet wheels each 35 more than a single turn in order to effect the desired degree of compression. It will thus be seen that I have provided a baler which is simple in construction and highly efficient in operation. Although primarily intended 40 for the baling of paper, it is obvious that other material, as, for instance hay, may be compressed into bales in my improved form of baler.

While I have shown and described one 45 specific form of my invention, I would have it understood that various changes and modifications may be made by those skilled in the art without departing from the scope of the invention, as defined in the appended 50 claims.

Having thus described my invention what I claim as new and desire to secure by Letters Patent of the United States is:

1. A baler comprising, in combination, a 55 frame-work having side walls and end walls, an intermediate wall associated with each end wall to form therewith an end chamber said intermediate walls having vertical openings, a baling chamber between said 60 end chambers, a pair of followers adapted to operate in said baling chamber to compress the material between them, said followers comprising each a compression member and an actuating bar, said bars extending 65 from one end chamber to the other

across said baling chamber, a rotatable shaft mounted in each end chamber and provided with a transverse opening, said shafts extending longitudinally of the frame-work in axial alignment with each other, a cable 70 passing through said opening and engaging the shaft at a point midway of the cable, whereby rotation of the shaft causes both ends of the associated cable to be wound upon the shaft or unwound therefrom, the 75 free ends of each cable being adapted for attachment to said bars, a ratchet wheel secured to each shaft, a hook-shaped hand lever for engaging said ratchet wheels to actuate the same, so that the followers are 80 simultaneously moved toward each other, and means for preventing reverse rotation of said shafts.

2. A baler comprising in combination, a frame-work having side walls and end walls, 85 an intermediate wall having vertical openings in its upper and lower portions associated with each end wall to form therewith an end chamber, said intermediate wall forming the end walls of the baling chamber, a pair of followers adapted to operate in said baling chamber to compress the material between them, a rotatable shaft journaled in each end wall and the associated intermediate wall substantially midway of the 90 end chambers, said shafts extending longitudinally of the frame-work in axial alignment with each other, connections in said end chambers between said shafts and said followers, so that rotation of said shafts 100 causes the followers to move toward each other simultaneously, and means on the outside of said end chambers for operating said shafts.

3. A baler comprising in combination, a 105 frame-work having side walls and end walls, an intermediate wall having vertical openings in its upper and lower portions associated with each end wall to form therewith an end chamber, said intermediate walls 110 forming the end walls of the baling chamber, a pair of followers adapted to operate in said baling chamber to compress the material between them a rotatable shaft journaled in each end wall and the associated 115 intermediate wall substantially midway of the end chambers, said shafts extending longitudinally of the frame-work in axial alignment with each other, the outer ends of said shafts projecting beyond the end walls of 120 the frame-work, connections in said end chambers between said shafts and said followers, so that rotation of the shafts causes the followers to move simultaneously toward each other, a lever wheel fixed to the outer end of each shaft on the outside of said end chambers, and a hand lever having a curved portion adapted to engage the periphery of the ratchet wheels when applied thereto, said curved portion terminating in a hook to en- 130

gage the teeth of the ratchet wheels for actuating said shafts, and means for preventing reverse rotation of said shafts.

4. A baler comprising, in combination a frame-work having side walls and end walls, an intermediate wall associated with each end wall to form therewith an end chamber, said intermediate walls having vertical openings said intermediate walls forming the 10 end walls of the baling chamber, a follower adapted to operate in said chamber to compress the material therein, a rotatable shaft journaled in each end wall and the associated intermediate wall substantially midway 15 of the end chambers, said shafts extending longitudinally of the frame-work in axial alinement with each other, connections in said end chambers between said shafts and said follower, so that rotation of the shafts 20 lowers the follower, and means outside of said end chambers for operating said shafts.

5. In a baler, a frame-work having end walls and side walls, a pair of end chambers and a central baling chamber arranged between said end walls and having vertical side openings, a follower movable in said baling chamber to compress the material therein, a shaft journaled in each end chamber longitudinally of the frame-work, operative connections housed in said end chambers between said followers and said shafts, and means on the outside of said end chambers for operating said shafts.

6. In a baler, a frame-work having end walls and side walls, a pair of end chambers and a central baling chamber arranged between said end walls said central chamber having vertical side openings, a pair of fol-

lowers movable in said baling chamber to compress the material between them, a shaft 40 journaled in each end chamber longitudinally of the frame-work, operative connections housed in said end chambers between said followers and said shafts, means outside of said end chamber for operating said 45 shafts, and means for preventing reverse rotation of said shafts.

7. A baler comprising, in combination, a frame-work having side walls and end walls, an intermediate wall associated with each 50 end wall to form therewith an end chamber, said intermediate walls each having vertical openings and forming the end walls of the baling chamber, a follower adapted to operate in said baling chamber to compress the 55 material therein, a bearing plate secured to each end wall and each intermediate wall, said four bearing plates being in axial alinement with each other, a shaft journaled in each pair of plates, the outer ends of said 60 shafts projecting, beyond the end walls of the frame-work, connections housed in said end chambers between said shafts and said follower for moving the latter downwardly 65 when the shafts are rotated, a ratchet wheel fixed to the outer end of each shaft, outside of said end chambers, a retaining pawl associated with each ratchet wheel to prevent reverse rotation of the shafts, and a hand lever for actuating said ratchet wheels to 70 lower the follower.

ALBERT E. BEALL.
